(74) Attorney, Agent, or Firm — Banner & Witcoff, Ltd.

(57) CLAIM

The ornamental design for a shoe as shown and described.

DESCRIPTION

FIG. 1 is a front perspective view of a shoe showing my new design in a first state;

FIG. 2 is an opposite side front perspective view thereof;

FIG. 3 is a top view thereof;

FIG. 4 is a front perspective view from the opposite side of the shoe shown in a second state; and,

FIG. 5 is a top view thereof.

The broken lines depicting the remainder of the shoe form no part of the claimed design.

1 Claim, 5 Drawing Sheets(56)
